UNITED STATES PATENT OFFICE.

KENNEDY DOUGAN, OF MINNEAPOLIS, MINNESOTA.

INTERNAL-COMBUSTION ENGINE.

1,262,758.

Specification of Letters Patent. Patented Apr. 16, 1918.

Application filed June 24, 1911, Serial No. 635,206. Renewed January 10, 1918. Serial No. 211,315.

To all whom it may concern:

Be it known that I, KENNEDY DOUGAN, a citizen of the United States, residing at Minneapolis, in the county of Hennepin and State of Minnesota, have invented certain new and useful Improvements in Internal-Combustion Engines, of which the following is a specification.

My invention relates to internal combustion engines and has in view providing an engine of that character in which the force of the explosion within the combustion chamber will operate to raise a weight vertically, the energy thereby accumulated being used to perform useful work when the weight falls, such, for instance, as operating the piston of a pump or air compressor or the stamps in a quartz mill. As at present constructed internal combustion engines cannot be efficiently used in operating pumps or air compressors because such engines are not adapted to a wide variation of speed, while the speed of pumps and air compressors is subject to the widest variation, and it is a feature of this invention that my engine will have an unlimited range in speed regulation and at the same time the thermal and mechanical efficiency will be uniformly high at whatever speed the engine may run.

A principal object of my invention is to arrange two or more explosive engine units in a frame, connecting the pistons of all said units with the weight to be lifted or a member adapted to lift such weights, and providing valve control sparking and carbureter mechanism for each unit so coördinated as to cause the engine units to operate in alternative succession, the return of the weight operating member always compressing a charge in the cylinder of one of said engine units while at the same time air or combustion gases or both will be exhausted from the other engine units.

A further object of my invention is to provide centrifugal means for opening the exhaust valves at a point just as the weight reaches the upward limit of its throw, said means correspondingly operating to close said valves just as the weight operating means reaches its lower point of movement, the valve operating means for the different engine units being so coördinated that the valve will be closed only in the engine unit in which a charge is being drawn in and

opened only in the engine unit in which a charge has been exploded.

A further object of my invention is to provide means for regulating automatically the proportions of fuel and air necessary to throw the weight operating means to the required height when combustion takes place, said means being adjustable to provide for throwing the weight to different heights, as desired.

A further object of my invention comprises means for regulating the number of strokes of the engine per unit of time which means consists of mechanism adapted to hold the weight-operating member at the upper limit of its stroke for any desired length of time before the same may fall under the influence of gravity to perform its work. It is also an object of my invention to combine with these means, when the apparatus is used to pump air or water, means subject to the pressure of the receiver for automatically increasing or decreasing the number of strokes of the engine to maintain said pressure constant at a given degree.

A further object of my invention is to provide means for igniting the compressed charge of whichever engine unit is in the explosion portion of its cycle at a point in the down stroke where the charge should normally be properly compressed and the weight operating means about to stop, igniting contact being determined solely by the fall of the weight-operating means and always taking place at the same point in said descent.

Other objects of my invention are to provide novel means for starting and stopping the engine, means for adapting the engine for pumping against high or low pressure, and other features of advantage which will appear in the detailed description of my invention and which are particularly pointed out in the claims.

In the drawings, illustrating the application of my invention in one form,—

Figure 1 is a side elevation of a portion of my device showing various coördinating parts for operating the same, the cylinders being ordinary single cylinders. Fig. 2 is an end elevation of the machine somewhat diagrammatic and on a smaller scale than Fig. 1 and with parts removed showing the application of the engine to an air com-

pressor. Fig. 3 is a similar side elevation partly in section and showing the use of double cylinder engine units. Fig. 4 is a detail view of certain parts shown in Fig. 2. Fig. 5 is a detail elevation view in vertical section of the air compressing cylinder, its valves and emergency piston checking means. Fig. 6 is an enlarged elevation view with some parts broken away, and Fig. 7 a similar plan view of the valve operating means. Figs. 8, 9, 10 and 11 are views of details of the valve operating mechanism. Fig. 12 is a fragmentary diagrammatic view somewhat similar to Fig. 2 showing single cylinder mechanism. Fig. 13 is a view of a modified form of the valve operating slide. Fig. 14 is a fragmentary side elevation and Fig. 15 a front elevation of means for connecting weights to the weight-operating member and releasing the same therefrom at the proper moment in the stroke of the engine. Fig. 16 is a vertical elevation view, partly in section, of a means for regulating the number of strokes of the engine per unit of time. Fig. 17 and Fig. 18 are enlarged sectional elevation and plan views, respectively, of a modified form for regulating the number of strokes which is adapted to be used when the length of the piston stroke is made adjustable. Fig. 17^a is a view of a detail of the structure illustrated in Figs. 17 and 18. Fig. 19 is a side elevation of the automatic operating mechanism for a magneto and the sparking device, Fig. 20 being a plan partly in section of the same mechanism. Fig. 21 is a diagrammatic representation of the sparking mechanism and connections. Fig. 22 is an elevation view, partly in section, of a modification of the means for regulating the length of the engine stroke shown in Fig. 1. Fig. 23 is an enlarged sectional elevation of the device for regulating the length of stroke shown in Fig. 1.

It is well known that the efficiency of explosive engines when used for pumping is very much diminished by reason of the fact that because of the changing condition of pressure within the fluid receptacle the engine speed must be constantly varied and frequently falls much below the maximum for any given stroke. Piston leakage, however, within the pump is always related to the time of the stroke, being least when the time of said stroke is shortest, so that the pumping efficiency will be highest when the engine is working so that each pumping stroke is effected at the maximum velocity. This is one of the novel and valuable results accompanying the use of my engine in pumping. Every pumping stroke is made at the maximum velocity, since the pumping stroke is produced by the acceleration of gravity upon the weight connected with the pumping piston from the same height for each stroke, and since the governing

mechanism provided does not permit the stroke to begin until the pressure of fluid within the receptacle falls to a point such as to permit action at such maximum velocity. It is also true that the explosion 70 within the cylinder will always take place with a full charge for elevating the weight to the particular height desired and which will be found to produce the best results in connection with any particular pump. Each 75 stroke of the engine, therefore, is also made at maximum velocity. There cannot be any misfiring or back stroke in an engine constructed in accordance with the principles of my invention. The explosion will always 80 operate to lift the weight, and as the member to which the engine pistons are connected has only a reciprocating movement, this action must always be in the direction for performing efficient work. Furthermore, 85 the charge drawn into the cylinder cannot be exploded until compressed to a certain extent, and in practice this compression will have always progressed to a point where 90 efficient action results from the explosion. 90

The main frame of my machine comprises upright members 1 and 2 secured to the floor or other foundation provided for that purpose, said members preferably extending in a substantially vertical direction but 95 approaching one another toward the top, as clearly shown in Fig. 2. Where the engine is designed to be used for pumping or air compressing purposes the cylinder 3 of said pump or air compressor will be mounted 100 centrally between standards 1 and 2, as shown in Figs. 2 and 3, and specifically with respect to air compressor mechanism, as shown in Fig. 5, 4 being the piston of the air compressor, 5 a piston rod having thereon an enlarged portion 6 for a purpose hereinafter described, 7 an inlet valve, and 8 a compression valve connected with a pipe 9 leading to a storage receiver, not shown, valves 7 and 8 being of a structure ordinarily employed in air compressor mechanism. The frame members 1 and 2 are formed with inwardly extended lugs or brackets 10 and 11 to which are secured in vertical position, one above the other, cylinders 12 and 13 by means of clamping lugs 14 on said cylinders. Fig. 3 shows a double cylinder construction in which cylinder members 15 and 16, of a type similar to that disclosed in my patent application number 110 474,042, filed January 25, 1909, are used, since it is within the scope of my invention to use an engine of that type as well as an internal combustion engine employing single cylinders such as cylinders 12 and 13, shown 115 in the other figures of the drawings. Secured to the top ends of uprights 1 and 2 is a cylinder 17 for a purpose to be later described, member 2 preferably being bolted directly to the bottom of said cylinder 120 125 130

at 18, as shown in Figs. 2 and 3, while the upper end of member 1 is secured to lugs 19 on the side of cylinder 17, as clearly shown in Figs. 1 and 2. Each of cylinders 5 12 and 13 is provided with a piston 20 having the usual piston rod 21, the lower of said rods being secured, either rigidly or so as to permit freedom of movement, as desired, to a cross-bar 22 and the upper to a 10 cross-bar 23 of a yoke weight-operating device 24, said yoke being thereby suspended to hang freely between the frame members 1 and 2, preferably at right angles to the plane thereof, as shown. In the form shown 15 in Fig. 3 the double pistons 25 and 26 have both piston rods 27 and 28 thereof secured to said cross-bars 22 and 23, respectively. To the top cross-bar 23 is secured an additional upright U-shaped member 29 which 20 may be formed integrally with the yoke 24, the top cross piece 30 of said member 29 having secured thereto the rod 31 of a piston 32 for a purpose later to be described.

As shown in Fig. 12, I may pivot each 25 of pistons 4, 20, and 32 to piston rods 5, 21, and 31, and also pivot piston rods 21 to cross-bar 22 and 23, respectively, as indicated at 21', but in this construction piston rod 5 will be rigidly secured to weight 33, 30 and piston rod 31 will be rigidly secured to cross-bar 30.

In the form of the engine designed for pumping or air compressing purposes I 35 preferably secure directly to the bottom ends of yoke member 24 a weight 33 which may be large or small in proportion to the cylinders employed and the power to be derived therefrom. The weight may be formed at the lower end thereof with a cylindrical 40 portion 34 having a flat bottom surface adapted to seat within the cylindrical cavity 35 formed by a cup-shaped member 36 held in supporting extensions 37 formed on uprights 1 and 2, as shown in Fig. 5, the member 36 being provided with a guide opening 38 for the piston 5 of the compressor or 45 pumping mechanism. The weight will also be provided with a centrally disposed cylindrical cavity 39 of substantially the same 50 cross sectional area as the enlarged portion 6 of the piston 5, within which the said enlarged portion 6 will be rigidly positioned, so that when the weight falls the piston 4 will be thrust downward compressing air 55 or forcing water, as may be desired, lifting of the weight also lifting the piston and permitting air to enter through valve 7. The cylindrical receiving cavity 39 provides a safety air cushion to prevent accident in 60 case for any reason the weight should drop past the normal limit of its stroke.

A carburetor 40 of ordinary construction is secured upon the lower end of each cylinder being provided with common valve mechanism 65 41, the fuel supply pipe 42 leading to

the carburetor having therein a valve 43 in the form of regulating device shown in Fig. 1. This valve has secured thereto an arm 44 normally held in open position by a spring 45, the end of this valve being pivotally connected by a link 46 with a piston 47 operating in an open-topped cylinder 48, all of these parts being secured to frame member 2 by means of a bracket 49. Adjacent the cylinder 48 and secured to the 70 bracket 49 is another cylinder 50 within which works a piston 51 having pivotally connected therewith a rod 52, said rod pivotally connecting at 53 with one arm 54 of a trip pivoted at 55 to a bracket 56 extending from frame member 2. Extending inward from the pivot point 55 the lever 54 is provided with another arm 56' to which is attached a spring 57 secured to the end of a bracket 58 extending out from the frame 80 member 2. The arm 56 is provided with a foot-like member 59 which extends into the path of a trip 60 adjustably secured to the yoke 24, the adjustment being provided by means of a bolt 61 operating in a slot 62 extending longitudinally of said yoke member 24. By means of this bolt and slot the trip 60 may be placed in different positions upon the yoke member 24 so that the same will engage the extension 59 and operate 90 lever 54 at different points in the upward stroke of said yoke member. Cylinders 48 and 50 each contain a certain amount of oil. Two pipes 63 and 64 open into the bottom 100 of cylinder 48, pipe 63 extending directly into the bottom of cylinder 50 and having therein an upwardly opening check valve 65, while pipe 64 enters the cylinder 50 at a point 66 in the side thereof above the normal upper position of piston 51. The 105 pipe 64 may be provided with a choke valve 67 to regulate the rate at which oil may flow through said pipe from cylinder 48 into cylinder 50 above piston 51. The piston 51 is provided with a downwardly opening 110 valve 68. In operation, when the charge in the engine cylinder explodes, if the yoke is thrown too far upward, the trip 60 will engage the member 59 and through arm 54 and link 52 force piston 51 downwardly 115 thereby forcing oil from cylinder 50 into cylinder 48 below piston 47 which will lift piston 47 and through link 46 and arm 44 tend to close valve 43 and diminish the supply of fuel to the engine. The oil beneath 120 the piston 47 is prevented from returning through pipe 63 by valve 65 but will flow back through pipe 64 above the piston 51 from which position it may pass through valve 68 below the piston 51. The co-operation 125 of these elements will supply fuel sufficient to keep the stroke of the engine so that trip 60 will reach and slightly actuate arm 56 at nearly every stroke. By shifting the position of the catch 60 on the yoke 24 130

the length of the engine stroke may be correspondingly varied. A governing mechanism, such as above described, will, of course, be used in connection with each 5 cylinder or engine unit.

Exhaust valves 69 and 70 provided on cylinders 12 and 13, respectively, are operated in coöordination by a set of mechanisms shown in detail in Figs. 7 to 11, inclusive, 10 which, being the same for each engine unit, will be described with reference to one only. The valve stem 71 is normally pressed down by spring 72 so as to hold the valve closed, as shown in Fig. 8. When in this position the 15 end of the valve stem engages a flat spring 73 secured upon the end of the bracket arm 74 on the bottom of the cylinder. Mounted in another bracket 75 extending from the bottom of cylinder 13 is a shaft 76 carrying a cam 77 20 having a raised portion adapted to engage the spring 73. This cam has pivotally connected to the inner peripheral portion one end of a link 78 the other end being pivotally connected at 79 with one arm 80 of a bell 25 crank pivoted at 81 to a rod or casting 82 extending from the frame member 2, the other arm 83 of said bell crank having an extension 84 which engages within a fork 85 on the end of a lever 86 mounted to slide 30 in a bearing on a bracket 87 secured to frame member 2. The sliding lever 86 is continued upwardly and secured to a member 88 offset in parallel relation with lever 86 and having an upper extension 89 mounted to slide 35 in a bearing within a bracket 90 secured to frame member 2. Member 87 is provided with a series of upwardly pointing ratchet teeth 91, member 88 having a corresponding series of downwardly pointing ratchet teeth 92. A bracket arm 93 is secured to the yoke 40 45 24 extending forwardly to a point midway between members 86 and 88, said bracket being provided with a pivotal extension 94 vertical with respect to the plane of members 88 and 86, upon which is mounted a double ended pawl 95 the upper and lower ends of which point respectively toward the rack teeth 92 and the rack teeth 91. Pivoted to the pawl 95 at a point 96 at one side of 50 the pivot 94 is a link 97 the other end of which is formed with a slot 98 adapted to receive a pin 99 on one end of an arm 100 secured to a rock shaft 101 mounted in a long bearing 102 carried by a bracket 103 55 secured to yoke member 24, the other end of said rock shaft having fast thereon an arm 104 having secured to the end thereof by ball and socket joint 105 one end of a governor rod 106. The other end of rod 106 60 is connected by ball and socket joint 107 to a lever 108 pivoted at 109 to cross member 23. Movement of lever 108 will, through connecting mechanism just described, operate to throw pawl 95 into engagement 65 with rack 92 or rack 91 according to whether

yoke 24 is approaching the upper or lower portion of its stroke.

To accomplish this result I have provided centrifugal means operated by and dependent for its operation upon the movement of the said yoke member up or down in the course of its stroke. Secured upon the inner side of frame member 2 is a rack 110 with which engages a pinion 111 upon a shaft 112 mounted in bearings 113 and 114 in 70 arm portions 115, 116, respectively, of a bracket member 117 secured to cross bar 23. A hub 118 is secured to shaft 112 adjacent to bearing 114, said hub having pivotally connected thereto pairs of links 119 and 120, 75 which links are in turn pivotally connected to oppositely disposed weights 121, 122, the said weights being also pivotally connected to other pairs of links 123 and 124, said last named pairs of links being pivotally connected to a hub 125 formed on a sleeve 126 80 slidably mounted on shaft 112. Connected to the pivot pins 127 extending through weights 121 and 122 are spiral springs 128 normally tending to draw the weights together and force the sleeve 126 inward on the shaft 112. The sleeve 126 is provided with a collar 130 engaging an annular recess in an enlarged portion 131 on a sleeve 132 85 mounted to slide freely on shaft 112, said sleeve being held from rotation on said shaft by means of a bifurcated extension 133 on sleeve 132 straddling a web 134 on bracket member 117. Lever 108 is formed with a yoke 135 straddling the shaft 112, and to the 90 independent arms of said yoke are pivoted links 136 and 137, said links in turn being pivotally connected to sleeve 132 at 138, 139, as clearly shown in Fig. 6. Movement of sleeve 132 on shaft 112 will therefore be 95 communicated to shaft 108 and through connecting mechanism to pawl 95, this movement being caused by the centrifugal action of the weights 122, which will be thrown out as yoke member 24 moves upwardly, but 100 which, near the termination of said stroke, as their rate of revolution diminishes, will be drawn together by the springs 128, finally moving arm 100 so as to effect engagement 105 of pawl 95 with the upper rack 92 and opening the exhaust at the end of the stroke. The bearings in brackets 87 and 90 are made tight so that member 86 will remain in any given position. The exhaust valve will remain open until the mechanism is positively 110 actuated again through engagement of the lower end of pawl 95 with rack 91, which operation will normally be effected in exactly the same manner, as the yoke 24 and connected pistons reach the termination of 115 the return or falling stroke. The extent of movement of sleeve 132 may be adjusted by means of a hand screw 140 threaded into a bearing 141 in a bracket 142 upon member 120 143, the end of said screw 140 being con- 125 130

nected by means of spiral spring 143 with a bifurcated piece 144 pivoted to arm 108 near the point of connection thereof with bracket member 117. By manipulating hand 5 screw 140 the extent of movement of arm 108 may be resiliently controlled.

Since the engine units forming my device as a whole must remain alternatively inoperative, in the form shown, where two of 10 such units are used, one only compressing a charge on the return stroke, it follows that the valve operating mechanism must be held inoperative for each alternate stroke. This result is secured by means of the following 15 mechanism. In a bracket 145 is journaled a shaft 146 having secured thereto a sleeve 147 on which is a cam member 148, said cam member being in the form of a web or rod entering between the bifurcated ends 149 20 of a lug 150 on sleeve 132, the cam 148 being of such shape that each movement of the sleeve 132 backward and forward along shaft 112 will rotate the sleeve through half a revolution or 180 degrees. Fig. 10 shows 25 an end view of cam and connected parts. As shown, secured to sleeve 147 and cam 148 is an arm 151 to which is pivoted a pawl 152 engaging a two-toothed ratchet 153 formed integrally with a pinion 154 rotatable on 30 shaft 146. Pinion 154 meshes with a gear 155 on a stub shaft 156 mounted in a bearing in bracket arm 145. The gear 155 has thereon a stop member 157 adapted at each 35 revolution of gear 155 to be placed in front of sleeve 132 so as to prevent movement thereof inward beyond a certain point. Cam 148 is so formed that the first portion of the inward movement of sleeve 132 will operate, through pawl 152 and ratchet 153, to rotate 40 gear 155 a half revolution, the pin and slot connection 99, 98 of arm 100 with lever 97 permitting this movement without actuation of pawl 95. If stop 157 is thereby brought into operative position with respect to the 45 inner end of sleeve 132 said inner end will engage the stop and further movement of the sleeve will thereby be prevented, thus preventing operation of pawl 95 during that stroke of the cycle. When sleeve 132 is 50 drawn out through the centrifugal action of plates 121 and 122 action of bifurcated lug 150 upon cam 148 will swing arm 151 back a half revolution bringing pawl 152 into engagement with the other tooth of ratchet 55 153 whereby upon the return of sleeve 132 gear 155 and stop 157 carried thereby are rotated a further half revolution thus taking the stop out of the path of movement of sleeve 132 and permitting said sleeve to 60 operate pawl 95 and through it the sliding member 86 and valve 70 on both the upward and descending strokes of the engine and yoke 24.

The stops 157 are differentially placed in 65 the valve operating mechanism of each en-

gine unit so that said valves will be rendered operative or inoperative in successive timed relation in accordance with the position in the cycle of operation of the entire engine. If more than two engine units were used a 70 plurality of stops 157 would be provided the position of which and the movement thereof by means of cam 148 and pawl 152 would be timed and regulated to bring about the operation of each engine unit at the proper 75 time in the entire cycle of operation.

A modified form of the slide for operating the valves is shown in Fig. 13. In this modification the bracket 93 and operating link 94 are as shown in the preferred form, 80 lower slide lever 158 having a fork 159 for engaging member 84 on bell crank 83. In place of the simple bearings in brackets 87 and 90 antifriction rollers 160 are provided between which lower arm 158 and upper 85 arm 161 travel, other antifriction rollers 160 being provided to engage the outer sides of the oppositely disposed portions of arms 158 and 161, the whole device being held in balanced condition by means of the weight 90 162 pivoted to the frame at 163 and pivotally connected by means of link 164 with the valve operating slide. In place of the pawl 95 a member 165 is centrally pivoted to the bearing portion 94 of arm 93, said 95 member in turn being pivotally connected at 166 with link 97. The member 165 is formed to be a little shorter through its longest dimension than the distance between the oppositely disposed portions of arms 158 100 and 161, which portions are slightly offset laterally, as shown at 167 and 168. The mechanism is shown in Fig. 13 as operative on the return stroke of the engine. The rounded end of the pivot member 165 105 engaging the offset portion 168 of the lever arm will have just sufficient grip thereon to slide the same sufficiently to operate the valve.

The ignition or sparking device may be 110 of any approved type, but an efficient device for the purpose is shown in Figs. 19 to 21, inclusive. In Fig. 21 the magneto 169, battery 170, wiring 171, and circuit closing switch 172 are diagrammatically shown. 115 As shown, the magneto 169 is secured upon a bracket 173 extending from frame member 2. The main support for the magneto and operating parts comprises a base 174 which is bolted to the bracket and which 120 carries an upstanding bearing member 175 having near the upper end thereof a bearing 176 for a shaft 177, a pair of additional upstanding members 178 providing bearings for shaft 179 which operates the mag- 125 neto proper 169. On the shaft 177 is a spur gear 180 meshing with a pinion 181 on the shaft 179. Secured to gear 180 so as to rotate therewith by means of sleeve 182 is a ratchet wheel 183, and this ratchet wheel 130

is adapted to be operated by a pawl 184 on the end of an arm 185, said arm being carried by a sleeve 186 loose on shaft 177. The sleeve 186 carries another arm 187 oppositely disposed from arm 185, said arm 187 having thereon a stub shaft 188 upon which is mounted a roller 189 in the path of movement of a plate cam 190 secured by bolts 191 to yoke member 24. A spring 192 is secured to a lug or pin 193 on arm 185 the other end of the spring being secured to a pin 194 on an upwardly extending arm 195 formed upon a bracket extension 196 of the member 178, this spring operating normally to hold pawl arm 185 retracted and roller 189 beneath the operative cam edge 197 of cam 190. When near the bottom of its stroke said cam edge 197 will engage roller 189 swinging arm 187 into the position shown in dotted lines and through the action of pawl 184 on arm 185 upon ratchet wheel 183 operating to turn said ratchet wheel and with it the spur gear 180 by which the magneto shaft 179 will be rapidly rotated to generate the charge required for an ignition spark. To insure that contact shall be made at the right point for igniting the charge when the same has reached the proper state of compression, switch 172 is mounted upon a short arm 198 on a rock shaft 199 carried in bearings in an arm 200 secured to frame member 1. Upon the inner end of rock shaft 199 is another arm 201 having on the end thereof a weight 202 and a cam roller 203 intermediate the weight and rock shaft, said cam roller being mounted on a stub shaft 204 extending outwardly from arm 201 so as to bring cam roller 203 into the plane of a long straight-sided cam 205 mounted upon the inner edge of yoke member 24. The cam 205 is provided with a cam surface 206 at such a point relatively on the yoke 24 that roller 203 may descend along said cam surface, as indicated in dotted lines in Fig. 19, with the result that adjustable contact pin 207 will reach contact 208 to close the circuit and cause a spark at the moment when the yoke should have reached the point in its descent where the charge is properly compressed and ignition should take place.

The cylinder 17 heretofore referred to may be of the form shown in Fig. 16 or that shown in Fig. 17. In the form shown in Fig. 16, which is the one of practical use for ordinary purposes, the cylinder 17 is really composed of the central portion 209 larger than piston 32 except for a short space, as shown at 210, and two side cylinders or by-pass passages 211 and 212, respectively. Passage 211 is provided with a valve 213 opening downwardly while passage 212 is provided with a choke valve 214 controlled by an arm 215, said arm being fast on the valve stem 214', as shown in

Fig. 1. The arm 215 has pivoted to the end thereof at 216 a link 217 connected with the piston in a cylinder 218 which cylinder may be supported by a bracket 219 secured to frame member 1. The cylinder may either be above valve 214, as shown in Fig. 16, or below, as shown in Fig. 1. Cylinder 218 forms a closed chamber and is connected by means of pipe 220 with the air receiver of the pump or air compressor, the pipe entering cylinder 218 on that side of the piston away from the side which is connected to link 217, the three compartments 210, 211 and 212 are filled with oil to near the upper ends thereof. When the yoke 24 is driven upward through passage 209 any oil carried up into the common passage-way 221 connecting the three chambers will pass downward through valve 213. The piston 32 fitting tightly in the diminished portion 210 of passage 209 will be held up and thus operate to hold up yoke 24 by oil trapped beneath said piston and the valve 213, unless valve 214 is open sufficiently to permit oil to flow upward by that route, until piston 32 comes into the enlarged portion of passage 209, when it will, of course, be entirely free to fall. The pressure communicated to closed cylinder 218 through pipe 220 may be sufficient wholly to close valve 214, in which case piston 32 and the parts connected thereto will be held in their upper position until pressure in cylinder 218 diminishes sufficiently to allow valve 214 to open.

In the form of device for controlling the strokes of the engine shown in Figs. 17 and 18, cylinder 17 is also provided with the double valve construction. The cylinder is divided centrally by a diaphragm 222 through which is secured an interior cylinder 223 in which piston 32 works tightly. Diaphragm 222 is provided with a series of downwardly opening valves 224 held in their raised positions by means of springs 225 encircling the valve stems and positioned between caps 226 on said valve stems and a projecting flange 227 on the interior of cylinder 17. The diaphragm 222 is additionally provided with a cylindrical opening 228 above which and having its inner diameter coincident therewith, extends a cylindrical cap 229 closed at the top but provided with openings 230 in the walls thereof, some of said openings extending into the upper portion of cylinder 17 above diaphragm 222 while other of said openings enter the cylinder 223, as shown. Adapted to close the openings 230 is a tubular slide valve 231, said valve operating in the cylindrical member 229 and being provided with oppositely disposed openings 232. Pivotable at 233 to a cross member 234 within the slide valve 231 is a link 235, the lower end of which is pivoted at 236 to an arm 237 on a

rock shaft 238 journaled in bearings in the walls of cylinder 17. Said rock shaft extends without cylinder 17 and has fast on an end thereof a double ended lever 239, 5 the ends 240 and 241 of said lever being offset, as shown in Fig. 17^a, and being pivotally connected to rods 242 and 243, respectively, rod 242 pivotally connecting with a piston 244 working in a cylinder 245 carried by a bracket 246 extending from cylinder 17, while rod 243 is pivotally connected at 247 with a cam actuating member 248 pivotally mounted on a stub shaft 249 extending from frame member 2. The member 15 248 is provided with a cam portion 250 which may extend into the path of a roller 251 on an arm 252 pivotally mounted at 253 upon the yoke member 24, arm 252 having an extension 254 which engages a stop 255 20 on yoke member 24 for limiting swinging movement of said arm 252 in one direction while permitting such movement in the opposite direction.

In the position of the parts shown in Fig. 25 17 the yoke member 24 has reached the upper limit of its stroke, cam member 250 has been actuated and through connections described has caused slide valve 231 to close openings 230. The lower portion of cylinder 17 below diaphragm 222 is full of oil, oil brought up by the upward stroke of piston 32 into the upper portion of said cylinder passing downward through valves 224. Since the piston 32 fits tightly in cylinder 223 the oil trapped beneath the same will hold piston and connected parts in raised position until tubular valve 231 opens passages 230. The piston 244 has connected thereto a rod 256, said rod having on the 40 lower end thereof a piston 257 fitting tightly into a short cylinder 258 which is expanded into a lower portion 259 of materially greater diameter than piston 257. A pipe 260 forms a by-pass opening into the contracted cylinder 258 and enlarged portion 259 of this cylinder, said pipe being provided with a hand operated choke valve 261 and a valve 262 controlled by an arm 263 similar to valve 214 and arm 215. Upon a 45 bracket 264 secured to frame member 1 a closed cylinder 265 is provided connecting by-pipe 266 to the compression chamber of the pump or air compressor. A piston within cylinder 265 is connected by link 267 with an arm 268 pivoted at 269 to a member 270 fast on cylinder 265, said arm 268 being provided with a fork 271 engaging a pin 272 on arm 263. When the pressure within the air compressor is sufficient to 55 hold valve 262 closed the parts will remain in the position shown in Fig. 17 with piston 32 and parts carried thereby in raised position. When said pressure relaxes permitting valve 262 to open, the oil trapped 60 in cylinder 259 may pass through pipe 260 above piston 257 which will permit said piston and piston 244 to fall (rapidly after piston 257 comes into enlarged cylinder 259) thereby causing slide valve 231 to open ports 230 and permit piston 32 and parts 70 carried thereby to descend.

In Fig. 22 is shown a modification of the means for regulating the length of the stroke. In this modification cylinders 48 and 50, piston 47 and rod 46 connecting the 75 same to the valve operating arm 44, together with pipe 63 connecting the bottoms of the two cylinders and upwardly opening valve 65 in pipe 63 are or may be identical in structure with the parts described with 80 reference to the other form. Cylinder 50 is, however, provided with a cap 273 closing the top of the cylinder excepting for a pipe 274 opening into said cylinder and into a cylinder 275 secured to bracket 56. The cylinder 275 is open at the bottom, and adapted to operate therein is a piston 276 upon a rod 277 threaded at 278 and adapted to be secured in adjusted position on a lug 279 on yoke 24 by means of a hand nut 280. 90 Cylinder 50 is filled with oil and the lower portion thereof is connected with the lower portion of cylinder 48 by a pipe 281 which extends through a valve 282 for regulating the rate of return of oil from below piston 95 47 to cylinder 50. Oil may also flow into cylinder 50 from above piston 47 through pipe 283 having therein an upwardly opening valve 284. The operation of this form of fuel supply governor is substantially the 100 same as that already described. The piston 276 enters cylinder 275 when the stroke is too long forcing air through pipe 274 into cylinder 50 and thereby forcing oil through pipe 63 beneath piston 47 to cause arm 44 to 105 operate valve 43 to cut off or lessen the fuel supply. When the stroke is too short oil will pass back from beneath piston 47 through pipe 281 allowing piston 47 to descend and through connected parts operate 110 valve 43 to increase the fuel supply.

Where it is desirable to lift weights independently of the yoke member 24, as, for example, in stamp mills, I may provide a weight 285 upon a rod 286 mounted to slide 115 in bearings in a frame 287, said rod having a bar 288 at right angles thereto adapted to be engaged by hooks 289 on a series of levers 290 depending from a shaft or stub 291 mounted in an extension 292 on frame 120 member 24, the hooks 289 on said arms being differentially placed so as certainly to engage the bar 288 on the rod 286. The upper ends of levers 290 are formed with cam extensions 293 adapted to engage a 125 wide roller 294 on a bracket 295 extending from cylinder 12 or frame members 1 or 2. As the yoke member rises one or the other of hooks 289 will catch on bar 288 thereby lifting weight 285. When member 24 130

reaches the upper end of its stroke the cam portion 293 of levers 290 will be engaged by rollers 294 thereby throwing the hook away from bar 288 and permitting weight 285 to drop.

In Figs. 2 and 4 I have shown a means for holding my mechanism inoperative, which also comprises a means for starting and stopping the engine. Pivoted to the frame member 1 at 296 is a bifurcated member 297 having arms 298 and 299 extending to either side of frame member 1 and normally held inwardly on said frame member by projecting spring 300. The arms 298 and 299 are provided with inwardly extending lugs 301 adapted to seat in cavities 302 formed in weight 33. The upper ends of arms 298 and 299 project outwardly, as shown at 303, and carry a pivot pin 304 on which is pivotally mounted a lever 305 having an eccentric head 306 engaging the side of frame member 1. By swinging the lever 305 down lugs 301 will be withdrawn from cavities 302 when weight 33 and yoke 24 will descend and the engine will thereby be started. When it is desired to stop the engine the lever 305 can be drawn upward, as indicated in dotted lines, which will permit lugs 301 to enter cavities 302 and sustain all of the parts in raised inoperative position.

The operation of the various features of my invention and the manner in which they are coördinated to produce the desirable results obtained have been fully given in connection with the detail description thereof and will be readily understood when considered in connection with such description and in relation to the drawings hereto appended.

I claim:

1. A force pump piston free to reciprocate variable distances and non-synchronously, a power weight moving in unison therewith and operating by gravity due to its inherent weight to move said piston against the resistance of the liquid in a direction to deliver liquid, and a fluid expansion motor having a piston movable variable distances in unison with the pump piston for elevating the weight and moving the pump piston reversely.

2. A force pump plant embodying a pump cylinder and piston, a vertically reciprocating mass of sufficient weight to effect by its descent under the influence of gravity alone the delivery stroke of the pump against the resistance of the liquid, and an internal combustion motor cylinder and piston connected with said weighted mass and free to reciprocate variable distances and non-synchronously to elevate the same without defining its upward range of movement or increasing its rate of descending movement, whereby the upward

movement may accord with economical speed for internal combustion engine practice and downward movement accord with the desired rate of pump delivery.

3. A pumping plant embodying a variable stroke vertically reciprocating mass of sufficient weight to perform by its descent under the influence of gravity alone the desired work in overcoming the resistance of and delivering fluid to be pumped, a power motor cylinder and piston connected therewith and adapted to elevate said weighted mass, the upward movement of said weighted mass being controlled entirely by the motor and the downward movement of said mass being controlled independently of said motor, whereby no isochronous relation exists between the said movements.

4. In a pumping mechanism, the combination with a fluid pump embodying a reciprocating member, a weight connected with said reciprocating member for imparting the delivery stroke thereto solely by the force of gravity, a single acting engine connected with said weight and reciprocating member for elevating the weight and restoring the reciprocating member, and means independent of said engine and weight for controlling the descent of the weight under the influence of gravity.

5. In a pumping mechanism, the combination of a fluid pump embodying a variable stroke reciprocating member, a weight associated with the said reciprocating member and movable therewith distances corresponding to variable strokes of said member and adapted by reason of its inherent weight to operate said member in one direction against the resistance of the fluid being pumped, and a single acting engine having a reciprocating member with a variable stroke in accord with the stroke of the pump member for elevating the weight to thereby store energy for effecting the reverse movement of the pump member.

6. In combination, a variable stroke reciprocating weight, fluid pumping means, connections between said means and said weight whereby said fluid pumping means is operated by the descending weight at a speed proportionate to the difference between the resistance being pumped against and the force exerted upon said weight by gravity, and internal combustion engine, and means connecting said engine and said weight, the construction being such that the weight is raised by the power stroke of said engine against the force of gravity to a variable height proportionate to the energy expended thereon.

7. An explosive engine comprising a plurality of engine units, and a single reciprocating member to which the pistons of all of said units are connected, a magneto, a circuit closer, means on the reciprocating

member for operating the magneto, and other means on the reciprocating member for releasing the circuit-closer, said sets of means operating in timed relation to ignite 5 a charge in any cylinder of said engine units at a point in the reciprocation of said member at which the charge is properly compressed.

8. An explosive engine comprising a plurality of engine units, and a single reciprocating member to which the pistons of all of said units are connected, a fuel supply governor, and means on the reciprocating member to operate said governor to regulate 15 the length of stroke of said reciprocating member.

9. An explosive engine comprising a plurality of engine units, and a single reciprocating member to which the pistons of all 20 of said units are connected, a fuel supply governor, means on the reciprocating member to operate said governor to regulate the length of stroke of said reciprocating member, and means to adjust said regulating 25 means to vary said length of stroke.

10. An explosive engine comprising a plurality of engine units, and a single reciprocating member to which the pistons of all of said units are connected, an ignition 30 system, means on the reciprocating member for operating said system, and means on the reciprocating member for effecting operation of the exhaust valves of the engine units, a fuel supply governor, and means on 35 the reciprocating member to operate said governor to regulate the length of stroke of said reciprocating member.

11. An explosive engine comprising a plurality of engine units, and a single member reciprocable through variable distances 40 to which the pistons of all of said units are connected, and means, including a member carried by said reciprocable member, for regulating the rate of reciprocation of the 45 engine.

12. An explosive engine comprising a plurality of engine units having the cylinders thereof arranged in a vertical line, a single reciprocating member to which the 50 pistons of all of said engine units are connected, a governor cylinder, a piston connected with said reciprocating member and working in said governor cylinder, said piston in the governor cylinder operating to 55 retard return reciprocation of said member, and pressure controlled means for releasing said last named piston to regulate the rate of reciprocation of the member.

13. An explosive engine comprising a 60 plurality of engine units, a single reciprocating member to which the pistons of all of said units are connected, a fuel supply governor and means on the reciprocating member to operate said governor to regulate 65 the length of stroke of said reciprocating

ing member and ignition system and means on the reciprocating member for operating said system, means on said reciprocating member for operating the exhaust valves of the engine units, and means including a 70 member carried by said reciprocating member for regulating its rate of reciprocation.

14. An explosive engine comprising a frame and cylinder vertically mounted therein, the piston rod of said cylinder 75 working upwardly, a weight-operating yoke mounted for reciprocation in said frame and having said piston rod secured thereto, a fuel supply governor, including a member on said yoke and a pair of connected cylinders secured to said frame, a piston working in one of said cylinders having connections for controlling said fuel supply, a piston working in the other of said cylinders having connections whereby said second piston may be operated by said member on the yoke, and a fluid in both 80 of said cylinders and valves to control the flow thereof for transmitting impulses from said second piston to said first piston. 90

15. An explosive engine comprising a frame and cylinder vertically mounted therein, the piston rod of said cylinder working upwardly, a weight-operating yoke mounted for reciprocation in said frame 95 and having said piston rod secured thereto, a magneto secured to the frame having an operating member therefor in proximity to a vertical member of said yoke, and a cam on said vertical member for engaging said 100 operating member during a portion of the stroke of said yoke.

16. An explosive engine comprising a frame and cylinder vertically mounted therein, the piston rod of said cylinder 105 working upwardly, a weight-operating yoke mounted for reciprocation in said frame and having said piston rod secured thereto, an ignition system, including a magneto and means on the yoke for operating the 110 same, a long cam on said yoke, a gravity operating switch centrally pivoted on the frame and having a roller engaging said long cam, said cam being formed to permit said roller to drop therefrom and the switch 115 to operate at a point in the descent of the yoke at which the charge in the cylinder will be properly compressed.

17. An explosive engine comprising a frame and cylinder vertically mounted 120 therein, the piston rod of said cylinder working upwardly, a weight-operating yoke mounted for reciprocation in said frame and having said piston rod secured thereto, an exhaust valve, a valve gear for operating 125 the exhaust valve, and centrifugal means and connections on the yoke for operating the valve gear.

18. An explosive engine comprising a frame and cylinder vertically mounted 130

therein, the piston rod of said cylinder working upwardly, a weight-operating yoke mounted for reciprocation in said frame and having said piston rod secured thereto, an 5 exhaust valve, a slide mounted in the frame and connections from said slide for operating the exhaust valve, an oscillating member on the yoke for engaging the slide, and centrifugal means on the yoke having connections to the oscillating member for causing 10 said oscillating member to engage the slide near the end of the stroke of said yoke.

19. An explosive engine comprising a frame and cylinder vertically mounted therein, the piston rod of said cylinder working upwardly, a weight-operating yoke mounted for reciprocation in said frame and having said piston rod secured thereto, an exhaust valve, a toothed slide and connections 15 for operating the exhaust valve, a pivoted dog adapted to engage and operate said slide, and centrifugal means on the yoke and connections to operate the dog.

20. An explosive engine comprising a frame and cylinder vertically mounted therein, the piston rod of said cylinder working upwardly, a weight-operating yoke mounted for reciprocation in said frame and having said piston rod secured thereto, an exhaust 25 valve, a slide having upper and lower sets of oppositely disposed teeth thereon and having connections to operate the exhaust valve, a centrally pivoted double dog the opposite ends of which are adapted to engage said upper and lower sets of teeth, respectively, and centrifugal means on the yoke and connections to operate the dog.

21. An explosive engine comprising a frame and cylinder vertically mounted therein, the piston rod of said cylinder working upwardly, a weight-operating yoke mounted for reciprocation in said frame and having said piston rod secured thereto, an exhaust valve, a slide and connections to operate the 30 exhaust valve, pivoted means adapted to engage the slide, a shaft on the yoke, means on the frame for rotating said shaft during reciprocation of the yoke, a centrifugal member rotatable with the shaft, a sleeve slidable on the shaft connected with and adapted to be slid along said shaft by said 35 centrifugal member, connections from said sleeve to said pivoted means, a stop, and means to bring said stop into the path of movement of said sleeve to prevent operation of said pivoted means on each alternate stroke of the engine.

22. An explosive engine comprising a frame and cylinder vertically mounted therein, the piston rod of said cylinder working upwardly, a weight-operating yoke mounted for reciprocation in said frame and having said piston rod secured thereto, an exhaust 40 valve, a valve gear for operating the exhaust valve, centrifugal means and connections on the yoke for operating the valve gear, and means to render said centrifugal

means inoperative to operate the valve gear on alternate strokes of the engine.

23. An explosive engine comprising a frame and cylinder vertically mounted therein, the piston rod of said cylinder working upwardly, a weight-operating yoke mounted for reciprocation in said frame and having 50 said piston rod secured thereto, an exhaust valve, a slide and connections to operate the exhaust valve, pivoted means adapted to engage the slide, a shaft on the yoke, means on the frame for rotating said shaft during 55 reciprocation of the yoke, a centrifugal member rotatable with the shaft, a sleeve slidable on the shaft connected with and adapted to be slid along said shaft by said 60 centrifugal member, connections from said sleeve to said pivoted means, a stop, and means to bring said stop into the path of movement of said sleeve to prevent operation of said pivoted means on each alternate stroke of the engine.

24. An explosive engine comprising a frame and cylinder vertically mounted therein, the piston rod of said cylinder working upwardly, a weight-operating yoke mounted for reciprocation in said frame and having 90 said piston rod secured thereto, an oil receptacle mounted in the frame above said cylinder comprising a cylinder, a piston connected with said yoke working in said last named cylinder, means for trapping 95 oil beneath said piston to hold the same and the yoke suspended, and means for releasing said trapped oil to permit the yoke to descend by gravity.

25. An explosive engine comprising a frame and cylinder vertically mounted therein, the piston rod of said cylinder working upwardly, a weight-operating yoke mounted for reciprocation in said frame and having said piston rod secured thereto, an oil receptacle mounted in the frame above said cylinder comprising a cylinder formed with a contracted portion near the upper end thereof and being gradually expanded above said contracted portion and expanded at 105 right angles to an element of said cylinder below said contracted portion, a piston connected with said yoke working in said last named cylinder and fitting snugly within the contracted portion thereof, means for trapping oil beneath said piston when it is positioned within said contracted portion, and means for releasing said trapped oil 110 to permit the piston and yoke to descend by gravity.

In testimony whereof I affix my signature in presence of two witnesses.

KENNEDY DOUGAN.
